DISPENSING DEVICE

Richard T. Cornelius, Minneapolis, Minn.

Application March 21, 1941, Serial No. 384,437

11 Claims. (Cl. 225—21)

My invention relates to beverage dispensing devices and particularly to devices adapted to be used in mixing syrups with carbonated water.

A still further object of the invention resides in providing a mixing device in which the amount of syrup may be accurately measured.

A feature of the invention resides in providing a device which will be extremely simple in construction and positive in action.

An object of the invention resides in providing a beverage dispensing device adapted to be rendered operable upon reduction of pressure in the pressure chamber.

A feature of the invention resides in providing a beverage dispensing device having a pressure chamber together with means for conducting carbonated water under pressure into the pressure chamber, and for controlling the ingress of the carbonated water in said chamber, said means being at all times in communication with the chamber.

Another object of the invention resides in providing means operable on occasion for controlling the egress of the carbonated water from said chamber and in constructing said means so that, when in operation, it offers less resistance to the flow of the water than the first named means to procure a reduction of pressure in the pressure chamber.

Another object of the invention resides in providing means for controlling the dispensing of syrup and means operable upon reduction in pressure in said pressure chamber for controlling said last named means.

Another object of the invention resides in providing pump means for dispensing the syrup, and in providing means operated by the reduction of pressure in the pressure chamber for controlling the operation of said pump means.

A feature of the invention resides in providing two expansible chambers having diaphragms therein, one of said diaphragms being subject to the pressure in the pressure chamber and serving to move the other diaphragm, the other diaphragm serving to pump the syrup.

Other objects of the invention reside in the novel combination and arrangement of parts and in the details of construction hereinafter illustrated and/or described.

In the drawings:

Fig. 1 is a plan sectional view of a beverage dispensing device embodying my invention and taken on line 1—1 of Fig. 2.

Fig. 2 is an elevational sectional view of the invention taken on line 2—2 of Fig. 1.

Fig. 3 is a sectional view similar to Fig. 2 showing the parts in altered position.

Fig. 4 is a fragmentary plan sectional view taken on line 4—4 of Fig. 3.

Fig. 5 is a detail sectional view of one of the valves of the invention.

My invention comprises a case 10 which is constructed with a body portion 11 having an upwardly facing surface 12 and a downwardly facing surface 13. Overlying the surface 12 is a cover 14 and attached to the surface 13 is a cap 15. These various parts are secured together to form within the interior of the case a pressure chamber 16, an upper compartment 17 and a lower compartment 18. The two compartments 17 and 18 are separated by a partition 19 and the said two compartments are disposed one above the other as clearly shown in Figs. 2 and 3. The cover 14 is formed with a neck 21 which is constructed with a passageway 22 communicating with the pressure chamber 16. Attached to this neck is a faucet 23 which will now be described in detail.

The faucet 23 is constructed with a body portion 24 integral with the neck 21 of case 10. The body portion 24 is provided with a vertical passageway 25 which communicates with the passageway 22 and which is provided at its lowermost end with a valve seat 26. The upper end 27 of the body portion 24 is threaded to receive a bushing 28 which is adapted to hold in position a tubular guide 33. This guide slidably supports a plunger 29. Plunger 29 is recessed as indicated at 31 to engage a shoulder 32 formed on the tubular guide 33. This shoulder limits the upward movement of the said plunger.

Within the passageway 25 is arranged a valve stem 34 which has secured to the lower end thereof a valve head 35 adapted to seat against the valve seat 26. The valve stem 34 is guided at its lower end in a perforated collar 36 mounted in the lower end of the body portion 24. The upper end of the valve stem 34 has attached to it a cylindrical head 37 which is slidably mounted in a washer 38 clamped to the upper end 27 of the body portion 24 by the bushing 28. Also clamped between said bushing and the body portion 24 is a small diaphragm 39 which is clamped to the valve stem 34 between a nut 41 and the head 37. A compression coil spring 42 encircling the stem 34 and seated against the nut 41 and guide 36 urges the valve head 35 into engagement with the valve seat 26. Another coil spring 43 acting between the washer 38 and the plunger 29 urges said plunger upwardly and away from the

head 37 to permit the spring 42 to move the valve head 35 into closing position. An adjusting screw 44 is threaded into the upper end of the plunger 29. When pressure is applied to this screw by means of any operating mechanism such as a lever or the like, valve stem 34 is depressed and the valve head 35 disengaged from seat 26 to permit of egress of liquid from the mixing chamber 16 and out of the device. To discharge the liquid from the faucet 23 a nozzle 45 is employed which is attached to the lowermost end of the body portion 24 in which the valve head 35 is movable.

Disposed on the surface 13 of the body 11 of casing 10 and between said body and the cap 15 is a diaphragm 46. This diaphragm is clamped in position between these two parts by means of screws 41 which pass through the cap 15, the body 11 and are threaded into the cover 14. The said diaphragm divides the compartment 18 into two chambers 48 and 49, which chambers are expansible and the volume of which is altered when the diaphragm is moved toward and from the partition 19.

Overlying the surface 12 of the body 11 and disposed between said body and the cover 14 is another diaphragm 53. This diaphragm is held in position between the said partition by means of the screws 47 previously referred to and by means of other screws 54 which extend through the body 11 and are threaded into the cover 14. The diaphragm 53 divides the compartment 17 into two expansible chambers 55 and 56, the chamber 56 being disposed adjacent the partition 19.

The diaphragm 53 has an extension 58 which extends outwardly beyond the confines of the compartments 17 and 18 and which is disposed in proximity to the portion 55 of the body 11, as well as the pressure chamber 16. This extension covers an annular valve chamber 52 formed in this part of the body. The said portion of the body is constructed with a number of concentric valve seats 57 which are adapted to be engaged by the diaphragm extension 58 which serves as the movable element of a valve indicated in its entirety by the reference numeral 59. The diaphragm extension 58 has a hole 61 in it which communicates with the pressure chamber 16. An annular leaf spring 62 engages the upper surface of the diaphragm extension 58 and urges the same into engagement with the valve seats 57. This spring is disposed within a recess 63 in the cover 14 and engages the lowermost wall 64 thereof.

The chamber 49 formed in compartment 18 is vented to the exterior and performs no particular function in the instant invention. The chamber 48, however, is connected by means of a passageway 51 with the valve chamber 52, previously referred to so that operation of the valve 59 will bring the chamber 48 into communication with the mixing chamber 16.

The partition 19 is formed with a bore 65 concentric with the diaphragms 46 and 53 which are disposed one above the other and in concentric relation. Slidably mounted in this bore is a sleeve 66 which makes a fluid-tight connection with the bore 65 through a packing gland 67. This sleeve at its upper end passes through the diaphragm 53 and also through two plates 68 and 69 overlying said diaphragm on opposite sides thereof. A nut 71 screwed upon the extreme upper end of the sleeve 66 clamps the said diaphragm and plates against a shoulder 72 formed on said sleeve. The sleeve 66 is similarly

constructed at its lower end and passes through the diaphragm 46 and through two discs 75 and 76 overlying said diaphragm upon the upper and lower surfaces thereof. A nut 77 screwed to the lower end of the said disc clamps these parts in place. By means of this construction the two diaphragms are secured together and are caused to move in unison.

The upper end of the sleeve 66 is formed with a head 78 which is threaded to receive a rod 79. Rod 79 passes freely through a hole 81 in the cap 15 and is threaded at its lower end, as designated at 82, to receive a nut 83 and a lock nut 84. The nut 83 engages the lowermost surface of the cap 15 and limits the upward movement of the two diaphragms 53 and 46. By adjusting the said nuts the volume of the expansible chambers can be manually regulated at will. A compression coil spring 85 encircles the rod 79 and is disposed within the bore 86 of the sleeve 66. This spring is seated at one end against the head 78 of said sleeve and at its other end against a washer 87 overlying the cap 15. By means of this spring the two diaphragms are urged upwardly to their extreme position determined by nut 83, as shown in Fig. 3.

When the device is to be used for preparing soft drinks or similar beverages, carbonated water under pressure is directed into the chamber 55 by means of a construction shown in Fig. 1. For this purpose a tube 88 is employed which is disposed within a larger tube 89. Both tubes are wound in the form of a coil as indicated by the reference numeral 91, which coil may be placed at any desired locality between the source of carbonated water and the mixing device. The tube 88 has a fitting 92 connected to it which is secured to a bushing 93 screwed into a wall of the cover 14. This bushing brings the passageway 40 in the tube 88 into communication with the chamber 55 through the said bushing. Attached to the tubes 88 and 89 at the ends of the tube 89 are suitable fittings 94 and 95 by means of which the annular passageway between the two tubes 45 may be connected to suitable pipe connections 96 and 97. The tube 89 forms a jacket encircling the tube 88 through which cooling liquid may be circulated to maintain the carbonated water passing through said tube at a proper reduced temperature. The tube 88 is of such dimensions as to offer an appreciable resistance to the flow of the carbonated water so that, when faucet 26 is opened a material reduction in pressure in the chamber 55 and in the pressure chamber 16 occurs which is utilized in the operation of the diaphragms 53 and 46 as will be hereinafter more fully described.

The syrup to be mixed with the carbonated water is directed to the bore 98 of a fitting 99 which is screwed into the body 11 of case 10. The body 11 of case 10 has a passageway 102 which communicates with the bore 98 and which brings said passageway into communication with the chamber 56. The fitting 99 has a check valve 101 in it which permits of entry of syrup into the device but prevents flow of syrup back out of the said device.

In the partition 19 is provided a check valve 103, best shown in Fig. 5. A passageway 104 extends through the partition 19 and is tapered to form a valve seat 105. A valve head 106 seats against this valve seat. This valve head has a stem 107 extending through the passageway 104, which stem has secured to it a spiral spring 108 received with a recess 109 in the uppermost por-

tion of said partition. By means of this construction the valve head 106 is maintained in closing position until the difference in pressure within the two chambers 56 and 49 causes the same to open against the action of spring 108.

Attached to the uppermost portion of the cover 14 is a jacket 111 which provides a space 112 overlying the chamber 55. Two pipe connections 114 and 115 are provided for the jacket 111 by means of which a cooling medium may be directed into and out of the space 112. Thus the cover 14 may be kept at the proper temperature to prevent undue pressure within the device and to maintain the carbonated water at the proper temperature.

The operation of the invention is as follows: When the two diaphragms 53 and 46 move upwardly, valve 103 is closed and the diaphragm 53 creates a suction in chamber 56 which opens the check valve 101 and draws a predetermined amount of syrup into said chamber from the source of syrup supply. When the diaphragm 53 reaches its uppermost position as controlled by nut 83 engaging the lowermost portion of the cap 15 the check valve 101 closes and cuts off the ingress of syrup. During the use of the device, as previously explained, the pressure in the pressure chamber 16 and the chamber 55 becomes appreciably reduced due to the resistance afforded by the tube 88 to the passageway of carbonated water through the same. While the pressure is so reduced the spring 85 forces the two diaphragms 53 and 46 upwardly to draw the syrup into the chamber 56.

Upon closing of the faucet 23 the pressure in the chamber 55 commences to build up until the said pressure is the same as at the beginning of the coil 91. As this occurs the diaphragm 53 is forced downwardly against the action of spring 85 and said spring compressed. During such movement the check valve 103 is opened and the syrup contained within the chamber 56 is discharged through the passageway 104 and into the chamber 48. At the same time that the diaphragm 53 is traveling downwardly to create pressure in chamber 56 to eject the syrup therefrom, diaphragm 46 is likewise traveling downwardly and creates a reduction of pressure in the chamber 48 which closes the valve 59 and also aids in opening the valve 103 and drawing the syrup from the chamber 56 and into the chamber 48. When the diaphragms reach their lowermost position, which is determined by the plate 76 engaging the cap 15, valve 103 closes and the syrup drawn into said chamber is cut off from the chamber 56. The parts then become arranged as shown in Fig. 2 which illustrates the normal positions of the parts when the faucet is closed. If now the faucet is opened, the pressure within the chambers 55 and 16 is reduced and spring 85 moves two diaphragms 53 and 46 upwardly. This causes injection of a new charge of syrup into the chamber 56 and at the same time causes discharge of the syrup in the chamber 55 through passageway 51 and valve 59 into the pressure chamber 16. Thus a predetermined measured quantity of syrup is discharged into the flowing stream of carbonated water as the same passes through the pressure chamber 16 and into the faucet 26. When the carbonated water is being filled in a glass of a certain size a predetermined amount of carbonated water is thus measured and likewise a predetermined amount of syrup is measured by the pumping action of the diaphragms 53 and 46. Thus a fixed amount of

syrup is discharged for each glass of beverage which is accurately measured and which can be controlled in amount by adjustment of the nuts 83 and 84.

The advantages of my invention are manifest. An extremely simple and practical construction is provided by means of which a predetermined amount of syrup may be delivered for each glass of beverage drawn from the device. The device functions solely upon reduction in pressure in the pressure chamber whereby no complicated or intricate parts are required for successful operation of the invention. The device is extremely small and compact and may be easily installed in close quarters. By the proper cooling of the case of my invention and the coil for conducting the carbonated water to the device, excessive pressures are prevented, thus making the device operate positively and procuring the proper dispensing of the syrup and the carbonated water. With my invention the quantity of syrup furnished may be readily regulated and controlled within close limits.

While I have described the invention as particularly useful for a device in mixing and dispensing beverages, it can readily be comprehended that the device may be used for any other kind of liquids and with fluids as well.

Changes in the specific form of my invention, as herein disclosed, may be made within the scope of what is claimed without departing from the spirit of my invention.

Having described my invention, what I claim as new and desire to protect by Letters Patent is:

1. A dispensing device having a pressure chamber, means for conducting a fluid under pressure into said pressure chamber said means including a fixed resistance for controlling the rate of ingress of the fluid into said chamber, said means being at all times in direct open communication with said chamber, means operable on occasion for controlling the egress of fluid from said chamber, said first and second named means being both in communication with said chamber during egress of fluid therefrom said last named means when in operation offering less resistance to the flow of the fluid than said first named means to procure a reduction in pressure in said pressure chamber, means for delivering a predetermined quantity of another fluid, and means operable upon reduction of pressure in said pressure chamber for controlling the operation of said last named means.

2. A dispensing device having a pressure chamber, means for conducting a fluid under pressure into said pressure chamber said means including a fixed resistance for controlling the rate of ingress of the fluid into said chamber, said means being at all times in direct open communication with said chamber, means operable on occasion for controlling the egress of fluid from said chamber, said first and second named means being both in communication with said chamber during egress of fluid therefrom said last named means when in operation offering less resistance to the flow of the fluid than said first named means to procure a reduction in pressure in said pressure chamber, means forming an expansible chamber, a movable member operable in said expansible chamber to vary the volume thereof, means for conducting a second fluid into said expansible chamber, said movable member serving to discharge the contents of said expansible chamber into said pressure chamber, and means operable upon reduction in pressure

in said pressure chamber for controlling the operation of the movable member within said expandible chamber.

3. A dispensing device comprising a case having a pressure chamber, means for conducting a fluid under pressure into said pressure chamber and for controlling the ingress of the fluid into said chamber, said means being at all times in communication with said chamber, means operable on occasion for controlling the egress of fluid from said chamber, said last named means when in operation offering less resistance to the flow of the fluid than said first named means to procure a reduction in pressure in said pressure chamber, said case having a partition forming two compartments disposed adjacent one another, a diaphragm in one of said compartments forming with said partition an expandible chamber and being movable to vary the volume thereof, a second diaphragm in the other of said compartments forming with said partition a second expandible chamber and with a portion of the case on the opposite side thereof a third expandible chamber, said second diaphragm being movable to vary the volume of said second expandible chamber and responding in movement to the variation in pressure in said third named expandible chamber, valve means for bringing said first named expandible chamber into communication with said pressure chamber, valve means for bringing said second named chamber into communication with said first named chamber, said third named chamber being at all times in communication with said pressure chamber, means for conducting a second fluid into said second named expandible chamber, and means for connecting said diaphragms together to cause the same to operate in unison.

4. A dispensing device comprising a case having a pressure chamber, means for conducting a fluid under pressure into said pressure chamber and for controlling the ingress of the fluid into said chamber, said means being at all times in communication with said chamber, means operable on occasion for controlling the egress of fluid from said chamber, said last named means when in operation offering less resistance to the flow of the fluid than said first named means to procure a reduction in pressure in said pressure chamber, said case having a partition forming two compartments disposed adjacent one another, a diaphragm in one of said compartments forming with said partition an expandible chamber and being movable to vary the volume thereof, a second diaphragm in the other of said compartments forming with said partition a second expandible chamber and with a portion of the case on the opposite side thereof a third expandible chamber, said second named diaphragm being movable to vary the volume and said second expandible chamber and responding in movement to the variations in pressure in said third named expandible chamber, said case having a passageway for bringing said first named expandible chamber into communication with said pressure chamber, a check valve for preventing flow of fluid from said pressure chamber to said first named expandible chamber, said partition having a passageway therein for bringing said second named expandible chamber into communication with said first named expandible chamber, a check valve in said second named passageway for preventing flow from said first named expandible chamber to said second named expandible chamber, said third named expandible

chamber being at all times in communication with said pressure chamber, means for conducting a second fluid into said second named expandible chamber, a check valve for preventing flow through said means out of said second named expandible chamber, and means for connecting said diaphragms together to cause unitary movement thereof.

5. A dispensing device comprising a case having a pressure chamber, means for conducting a fluid under pressure into said pressure chamber and for controlling the ingress of the fluid into said chamber, said means being at all times in communication with said chamber, means operable on occasion for controlling the egress of fluid from said chamber, said last named means when in operation offering less resistance to the flow of the fluid than said first named means to procure a reduction in pressure in said pressure chamber, said case having a partition forming two compartments disposed adjacent one another, a diaphragm in one of said compartments forming with said partition an expandible chamber and being movable to vary the volume thereof, a second diaphragm in the other of said compartments forming with said partition a second expandible chamber and with a portion of the case on the opposite side thereof a third expandible chamber, said second named diaphragm being movable to vary the volume and said second expandible chamber and responding in movement to the variations in pressure in said third named expandible chamber, said case having a passageway for bringing said first named expandible chamber into communication with said pressure chamber, a check valve for preventing flow of fluid from said pressure chamber to said first named expandible chamber, said partition having a passageway therein for bringing said second named expandible chamber into communication with said first named expandible chamber, a check valve in said second named passageway for preventing flow from said first named expandible chamber to said second named expandible chamber, said third named expandible chamber being at all times in communication with said pressure chamber, means for conducting a second fluid into said second named chamber, a check valve for preventing flow through said means out of said second named chamber, and means extending through said partition and connecting said diaphragms together for causing simultaneous movement of said diaphragms.

6. A dispensing device comprising a case having a pressure chamber, means for conducting a fluid under pressure into said pressure chamber and for controlling the ingress of the fluid into said chamber, said means being at all times in communication with said chamber, means operable on occasion for controlling the egress of fluid from said chamber, said last named means when in operation offering less resistance to the flow of the fluid than said first named means to procure a reduction in pressure in said pressure chamber, said case having a partition forming two compartments disposed adjacent one another, a diaphragm in one of said compartments forming with said partition an expandible chamber movable to vary the volume thereof, a second diaphragm in the other of said compartments forming with said partition a second expandible chamber and with a portion of the case on the opposite side thereof a third expandible chamber, said second named diaphragm being movable to vary the volume and said second named expandible

- 5 pansible chamber and responding in movement to the variations in pressure in said third named expansible chamber, said case having a passageway for bringing said first named expansible chamber into communication with said pressure chamber, a check valve for preventing flow of fluid from said pressure chamber to said first named expansible chamber, said partition having a passageway therein for bringing said second named expansible chamber into communication with said first named expansible chamber, a check valve in said second named passageway for preventing flow from said first named expansible chamber to said second named expansible chamber, said third named expansible chamber being at all times in communication with said pressure chamber, means for conducting a second fluid into said second named chamber, a check valve for preventing flow through said means out of said second named expansible chamber, means extending through said partition and connecting said diaphragms together for causing simultaneous movement of said diaphragms, said second named diaphragm being urged towards said partition through pressure created in the pressure chamber, and resilient means for urging said diaphragm for movement in the opposite direction.
7. A dispensing device comprising a case having a pressure chamber, means for conducting a fluid under pressure into said pressure chamber and for controlling the ingress of the fluid into said chamber, said means being at all times in communication with said chamber, means operable on occasion for controlling the egress of fluid from said chamber, said last named means when in operation offering less resistance to the flow of the fluid than said first named means to procure a reduction in pressure in said pressure chamber, said case having a partition forming two compartments disposed adjacent one another, a diaphragm in one of said compartments forming with said partition an expansible chamber movable to vary the volume thereof, a second diaphragm in the other of said compartments forming with said partition a second expansible chamber and with a portion of the case on the opposite side thereof a third expansible chamber, said second named diaphragm being movable to vary the volume and said second expansible chamber and responding in movement to the variations in pressure in said third named expansible chamber, said case having a passageway for bringing said first named expansible chamber into communication with said pressure chamber, a check valve for preventing flow of fluid from said pressure chamber to said first named expansible chamber, said partition having a passageway therein for bringing said first named expansible chamber into communication with said first named expansible chamber, a check valve in said second named passageway for preventing flow from said first named expansible chamber to said second named expansible chamber, said third named expansible chamber being at all times in communication with said pressure chamber, means for conducting a second fluid into said second named expansible chamber, a check valve for preventing flow through said means out of said second named expansible chamber, means for connecting said diaphragms together to cause unitary movement thereof, and adjustable means connected to said diaphragm and extending through said case for limiting movement of said diaphragms to control the volume of said first named expansible chamber.
8. A dispensing device comprising a case having a pressure chamber, means for conducting a fluid under pressure into said pressure chamber and for controlling the ingress of the fluid into said chamber, said means being at all times in communication with said chamber, means operable on occasion for controlling the egress of fluid from said chamber, said last named means when in operation offering less resistance to the flow of the fluid than said first named means to procure a reduction in pressure in said pressure chamber, said case having a partition forming two compartments disposed adjacent one another, a diaphragm in one of said compartments forming with said partition an expansible chamber movable to vary the volume thereof, a second diaphragm in the other of said compartments forming with said partition a second expansible chamber and with a portion of the case on the opposite side thereof a third expansible chamber, said second named diaphragm being movable to vary the volume and said second named expansible chamber and responding in movement to the variations in pressure in said third named expansible chamber, said case having a passageway for bringing said first named expansible chamber into communication with said pressure chamber, a check valve for preventing flow of fluid from said pressure chamber to said first named expansible chamber, said partition having a passageway therein for bringing said second named expansible chamber into communication with said first named expansible chamber, a check valve in said second named passageway for preventing flow from said first named expansible chamber to said second named expansible chamber, said third named expansible chamber being at all times in communication with said pressure chamber, means for conducting a second fluid into said second named expansible chamber, a check valve for preventing flow through said means out of said second named expansible chamber, means for connecting said diaphragms together to cause unitary movement thereof, and a threaded rod attached to said last named means and extending through the case, said rod being guided for movement in the direction of movement of the diaphragm, and adjusting nuts on the rod for limiting the stroke of said diaphragms for varying the amount of said second fluid entering said mixing chamber.
9. A dispensing device comprising a case having a pressure chamber, means for conducting a fluid under pressure into said pressure chamber and for controlling the ingress of the fluid into said chamber, said means being at all times in communication with said pressure chamber, means operable on occasion for controlling the egress of fluid from said chamber, said last named means when in operation offering less resistance to the flow of the fluid than said first named means to procure a reduction in pressure in said pressure chamber, a diaphragm within said case forming pumping means, said diaphragm having a part integral therewith and forming a valve for bringing the pumping chamber of said pumping means into communication with said pressure chamber, and means responsive to the pressure in said pressure chamber for operating said pumping means.
10. A dispensing device comprising a case formed with a compartment having a movable member therein and forming an expansible chamber on each side thereof, means for conducting carbonated water under pressure into the

expansible chamber on one side of the movable member, said case being further formed with a mixing chamber communicating with said expansible chamber, means for conducting syrup into the expansible chamber on the one side of the movable member, means for reducing the pressure of the carbonated water in said mixing chamber and means operated by such reduction of pressure for operating the movable member to discharge the syrup into the carbonated water in the mixing chamber.

11. A dispensing device having a mixing chamber, means for conducting a fluid under pressure into said mixing chamber to create a pressure therein, said means including a fixed resistance

for controlling the rate of ingress of the fluid into said chamber, said means being at all times in direct open communication with said chamber, means operable on occasion for controlling the egress of fluid from said chamber, said last named means when in operation offering less resistance to the flow of the fluid than said first named means to procure a reduction in pressure in said mixing chamber, means for delivering another fluid into said mixing chamber and means operable upon reduction of pressure in said mixing chamber for controlling the operation of said means for delivering the other fluid into the mixing chamber.

RICHARD T. CORNELIUS.
